UNITED STATES PATENT OFFICE.

HENRIK OLAI OLSEN AND OSKAR NILSEN, OF TRONDHJEM, NORWAY.

STAVE-PLANING MACHINE.

Application filed September 11, 1919. Serial No. 323,062.

To all whom it may concern:

Be it known that we, HENRIK OLAI OLSEN, of Elvegaarden, Oen, Trondhjem, and OSKAR NILSEN, of Erling Skakkes Gate 51-A, 5 Trondhjem, in the Kingdom of Norway, have invented certain new and useful Improvements in Stave-Planing Machines; and we do hereby declare the following to be a full, clear, and exact description of the invention, such as will enable others skilled in the art to which it appertains to make and use the same, reference being had to the accompanying drawings, and to letters or figures of reference marked thereon, 10 which form a part of this specification.

This invention relates to machines for forming or planing cask staves of the kind in which the cutters for shaping the edges of the staves have inclined cutting faces 20 and means are provided to move the cutters vertically according to their position in relation to the stave. The distance between the cutters will thus always correspond to the correct shape of the stave and as the 25 cutter bearings are turnable on a common pivot (corresponding to the axis of the cask) the angular shape of the stave will always be correct independently of the various breadths of the stave materials. When a 30 comparatively broad stave is put into the machine the cutter bearings will be pushed outward so that the edge of the cutter steel will have a somewhat more angular position with the effect that the difference in 35 breadth at the ends of the stave and the middle part thereof is proportionally greater compared to that of a narrower stave.

The principal improvement in this machine is that after being automatically 40 moved outward to correspond with the breadth of a stave, the cutters are moved vertically by the passage of the stave, thereby giving it the correct bilge and angular shape. When the operation is completed the 45 cutters slip back to their primal position until a new stave is put into the machine. By this machine it is thus unnecessary to sort out staves of various breadths.

Referring now to the accompanying drawings:

Fig. 1 is a side elevation;

Fig. 2 a plan view;

Figs. 3, 4 and 6 detail views;

Fig. 5 is a view on a larger scale than

Figs. 1 and 2 of the cutters which operate 55 on the side faces and a portion of the regulating mechanism.

Fig. 7 is a detailed view on an enlarged scale of the ratchet wheel and associated mechanism.

Referring now to the drawings, 2 is the bed plate of the machine which is provided with friction reducing and work supporting rollers 3. The work 1 to be converted into a stave is pushed along the bed plate 65 2 over the rollers 3 and under a roller 4. The roller 4 is mounted on a horizontally arranged shaft 5 supported in bearings 6, 7. The bearings 6, 7 are such that the roller 4 is permitted to accommodate itself to work 70 of varying thicknesses. 8 is a driving pulley mounted on the shaft 5 on which is also mounted a second and smaller pulley 9, which through any suitable belting, drives a pulley 10 on a shaft 11 also carried in 75 bearings on the bed plate 2. The shaft 11 carries a roller 12 and the mounting of the shaft 11 is such that the roller 12 is able to accommodate itself to work of varying 80 thicknesses. The work passing under the roller 4 is guided by blocks 13, 14 which are pivotally mounted at 15, 16 respectively on the bed plate 2. The blocks 13, 14 are respectively connected with the ends of links 19, 20 which are connected at their other 85 ends with an arm 21 pivotally mounted at 22 on the bed plate 2. The pins which connect the links 19, 20 with the blocks 13, 14 respectively, also engage in curved slots 17, 18 in the bed plate 2. The blocks 13, 14 90 are thus compelled to assume a position symmetrical with the center line of the bed plate 2, and the work 1 is thus held centrally whether broad or narrow.

The rotation of the roller 4 causes the 95 work 1 to advance and pass under the cutters 24 which are shaped according to the contour it is desired to impart to the outer face of the stave. The cutters 24 are mounted on a cutter head 23 which cutter head is 100 mounted on a shaft 25, carried in bearings 26 and driven by a pulley 27 through belting. After the work has been operated on by the cutters 24 it passes onward and is operated on its side faces by cutters 30, 31 105 on cutter heads 28, 29 respectively. The having inclined cutting faces and mounted work 1 is moved past these cutters 30, 31

by the roller 12. The cutters 30, 31 are mounted so that they can be moved towards or from the center line of the bed plate and also vertically.

5 The shafts 32, 33 on which are the cutter heads 28, 29 are mounted in bearings 34, 35 which are pivotally mounted at 36, 37 and are guided and limited in their movements by the engagement of pins 38, 39 with slots 40, 41 in a frame-work supported below the bed plate 2. The shafts 32, 33 are driven by pulleys 42, 43 and the arrangement is such that the shafts 32, 33 are capable of endwise movement relatively to the bearings 34, 35 and the pulleys 42, 43. The bearings 34, 35 are also connected by pins 44, 45, with members 46, 47 of frames 48, 49 supported upon ball races 82 and 84 and held in place by additional races 81 and 83.

10 To guide the work 1 and to regulate the position of the cutters 30, 31 during the passage of the work between them, the mechanism next to be described is employed. Mechanism for the first-mentioned purpose

15 comprises blocks 50, 51 pivotally mounted at 52, 53 on the bed plate 2. The blocks 50, 51 are connected with the one ends of links 54, 55 respectively, which at their other ends are connected with an arm 56 mounted

20 on the upper end of a centrally located shaft 57. On to this shaft 57 is fastened by screw 59, member 58 having a slot 60. (See Figures 4 and 7.) Engaging the slot 60 is an arm 61 having an angular portion

25 pivotally engaging the rear face of a ratchet wheel 62, as shown at 61^a. This connection is of a loose nature, which will allow the arm 61 to rotate when actuated by shaft 57 through member 58. Only a very slight rotation will be necessary, as more fully described hereinafter, so that the extreme up and down position of the arm 61, due to the rotation of ratchet wheel 62, will not be sufficient to withdraw the same from the

30 slot 60.

Ratchet wheel 62, provided with teeth on its front face, is pivoted at 71 to the frame structure, and is provided with a slot in its upper portion concentric with its periphery

35 through which extends shaft 69 carrying pawl 63 engaging the teeth of the ratchet and having spiral spring 85 encircling itself, which tends to key the pawl in engagement with the ratchet teeth. The rear end of shaft 69 extends into the peripheral slot of the toothed wheel 67, more fully described hereinafter. When the blocks 50, 51 are now moved outwards which at most is a comparatively short distance the arm 56, through the shaft 57, arm 58, slot 60 and arm 61 turns the ratchet wheel 62. Backward motion of the ratchet wheel 62 is prevented by a pawl 63. The ratchet wheel 62 is connected with the bearings 34, 35 by

40 links 65, 64. Movement of the blocks 50, 51

thus causes corresponding lateral movement of the bearings 34, 35 and consequently also of the cutters 28, 29 which are thus placed at a distance apart suitable for operating on the side faces of the work 1. To bring the cutters back to their first position when the stave has been planed, the pawl 63 is moved out of engagement with the ratchet wheel 62 by a stud 66 contained in a groove 70 on a wheel 67 when this wheel has made 75 a complete revolution. The wheel 67 has teeth or grooves 68 which engage the work 1 as it is fed forward and the wheel 67 is thus caused to rotate in accordance with the feed of the work. To insure that the 80 wheel 67 is always in the correct position at the commencement of operations on a piece of work, the wheel is made out of balance so that it always tends to assume one position. Spring 100 connecting shafts 85 32 and 33 tend to cause the shafts 32, 33 to swing inwards when the pawl 63 comes out of engagement with the ratchet wheel 62. To regulate the vertical position of the cutters 30, 31 the wheel 67 has mounted off center thereon two members 73, 74 in a manner to allow the wheel to rotate while the upper portions of members 73, 74 ride in slots 75, 76, in bars of the frame 77, 78 (see Figs. 3 and 5). The bars 77, 78 are pivotally held 95 between the downwardly extending portions 79 and 80 of the frames 48, 49, as clearly shown in Fig. 3. The lateral movement of the arms 73, 74 will be limited to the extent of the respective slots 75, 76 as the wheel 62 100 revolves, the vertical movement imparted thereby to members 73, 74 causing the cutters 30, 31 to likewise rise and fall vertically. It will now be seen that when the wheel 67 is turned the members 73, 74 will impart 105 vertical movement to the frames 48, 49, and the cutters 30, 31 are therefore caused to move up and down so that they are at their highest position when acting on the ends of the stave and at their lowest position when 110 acting on the center of the stave, whereby, with cutters having inclined cutting faces as shown in the drawing, the staves are formed wider at the center than at their ends.

Owing to the manner in which the bearings 34, 35 are connected with the frames 48, 49 the vertical movement of the cutters can take place independently of the side movements thereof.

What we claim is:—

1. A stave planing machine comprising a work support, tapering cutters mounted upon shafts carried by said support adapted to have vertical and lateral movement to shape the edges of the stave, a centering device for the work mounted forward of said cutters, and means for controlling the vertical motion of said cutters, said centering device including an equalizing bar mounted upon a shaft contained in the central longi- 125 130

tudinal plane of the machine which shaft rocks in accordance with the width of the stave and moves the cutter shafts to space them laterally for such width.

- 5 2. A stave planing machine comprising a work support, tapering cutters mounted upon shafts carried by said support adapted to have vertical and lateral movement, and to shape the edges of the stave, a centering 10 device for the work mounted forward of said cutters, controlling the lateral motion of the cutters, and means for controlling the vertical motion of said cutters, including a toothed wheel engaging the work having 15 arms mounted thereon pivotally engaging a framework supporting said cutters, and

adapted to actuate the cutters vertically upon the rotation of said wheel.

3. A machine such as covered by claim 2 in which said toothed wheel and centering 20 mechanism are provided with means which coact to allow the cutters to return to their initial position, ready to act upon a new stave.

In testimony that we claim the foregoing 25 as our invention, we have signed our names in presence of two subscribing witnesses.
